United States Patent Office.

JAMES WILLIAM BURNS, OF MEDWAY, OHIO.

Letters Patent No. 99,151, dated January 25, 1870.

IMPROVED CURTAIN AND MAP-FIXTURE.

The Schedule referred to in these Letters Patent and making part of the same

To all whom it may concern:

Be it known that I, JAMES WILLIAM BURNS, of Medway, in the county of Clark, and State of Ohio, have invented a new and useful Improvement in Curtain and Map-Fixtures; and I do hereby declare that the following is a full and exact description of the same, reference being had to the accompanying drawings, and to the letters of reference marked thereon.

This invention consists in the arrangement of certain simple devices, hereinafter fully described, in such manner that a curtain or map may be so hung as to be rolled up from the bottom, or lowered from the top, at will, and, at the same time, remain stationary in any position in which it may be fixed.

In the drawings—

Figure 1 represents a front elevation of a window-frame with a curtain hung in my improved method, and

Figure 2, a central vertical section of the same.

To enable others skilled in the art to make and use my invention, I will now proceed to describe my invention.

A represents a window-frame of the ordinary construction.

B represents a curtain or map, which is provided, at the bottom, with a roller, b, and at the top with a rod or bar, b'.

c c c c represent screw-rings, which are affixed to the frame at the centre and sides, as shown.

d d represent the centre cords, the upper ends of which are attached to the top rod of the curtain at its centre. The other ends, after passing about the curtain, and through the centre ring c c, is provided with a weighted tassel, as shown.

e e represent the side cords, the upper ends of which are attached to the rod of the curtain, as shown, their lower ends also being provided with weighted tassels.

The operation is as follows:

If it is desired to roll up the curtain, supposing it to be down, the centre cord is pulled until the curtain is sufficiently raised. If it is desired to lower it from the top, the side cords are simply raised.

It will be at once perceived that the curtain may be placed in any desired position by the proper manipulation of the cords.

The tassels should be so weighted as to balance the curtain or map.

By the simple arrangement herein described, a map or curtain may be hung at a very small expense, and yet be capable of being easily operated from the top or bottom, at will.

I am well aware that the separate elements of my invention are old in themselves, and I do not, therefore, claim them; but, having thus fully described my invention,

What I claim as new, and desire to secure by Letters Patent, is—

In combination with the cords d d, for rolling the curtain from the bottom, the cords e e and rings c c, for operating the bar b' from the top, as described, for the purpose set forth.

This specification signed and witnessed, this 9th day of September, 1869.

JAMES WM. BURNS.
